UNITED STATES PATENT OFFICE.

JESSE WALRATH, OF RACINE, WISCONSIN.

PORTABLE STEAM-ENGINE.

SPECIFICATION forming part of Letters Patent No. 284,344, dated September 4, 1883.

Application filed July 10, 1883. (No model.)

To all whom it may concern:

Be it known that I, JESSE WALRATH, a citizen of the United States, residing at Racine, in the county of Racine and State of Wisconsin, have invented certain new and useful Improvements in Portable Steam-Engines; and I do hereby declare the following to be a full, clear, and exact description of the invention, such as will enable others skilled in the art to 10 which it appertains to make and use the same.

This invention consists, mainly, in mounting a portable steam-engine on runners, and in arranging the steam-engine diagonally, so that while the fly-wheel remains as elevated as need be the cylinder is seated comparatively low down and the strains due to the working of 15 the engine are less severe on the boiler.

In order that my invention may be clearly understood, I have illustrated in the annexed 20 drawings, and will proceed to describe, the best form thereof at present known to me.

Figure 1 is a perspective view of my improved portable steam-engine. Fig. 2 is a rear end view, the rear standards for the support 25 of the end of the boiler being omitted, so as to better illustrate the feed-water heater. Fig. 3 is a sectional side elevation of parts of the machine, illustrating the use of a feed-water pump operated from the rock-shaft of the 30 valve-gearing of the steam-engine, in lieu of the steam-pump shown in Fig. 1.

The same letters of reference indicate identical parts in all the figures.

The boiler A is of the ordinary locomotive-boiler type. It is mounted on two long skids or runners, B B', by means of brackets *aa*, secured to the fire-box and standards A' at the rear end, as clearly shown in Fig. 1. The boiler is mounted just high enough so that the ash-pit A², which may be made detachable, will 35 clear the ground.

The steam-engine, which may be of any desired type, a slide-valve engine being shown, is arranged on one side of the boiler at an angle of, say, twenty degrees, more or less.

I prefer to use a feed-water heater, C, of any preferred internal construction, in connection with this portable steam-engine, and to mount it horizontally and transversely under the barrel of the boiler, it being provided or constructed with a suitable stand, *c*, at each end, for support on the runners B B'. It is also

provided with a saddle, *c'*, as an additional support for the forward end of the boiler, which may be loosely seated in such saddle or be 55 bolted thereto in such a way that the boiler, in expanding and contracting, may slide in the saddle.

The cylinder D of the steam-engine is constructed with an inclined base-plate, *b*, which is bolted to a correspondingly-inclined plate, *c*, formed on the stand *c* at one end of the feed-water heater. The cylinder end of the steam-engine is supported solely on this stand of the feed-water heater, and is entirely disconnected 60 from the boiler. The main shaft F of the steam-engine is located across the top of the boiler over the fire-box. Its end carrying the crank-wheel is supported in a bearing, H, formed on the forward upper end of the main frame E of 65 the steam-engine, which bearing is fitted and bolted to a seat, G, bolted to the boiler. A similar seat, G', is bolted to the boiler on the other side, for the support of the out-bearing H' of the main shaft, which carries the usual 70 fly-wheel pulley, K, on the outer side of such out-bearing. The bearings H H' are so arranged that their base-lines are parallel to the axis of the cylinder. The rock-shaft I, which transmits the motion of the eccentric on the 75 main shaft to the slide-valve in the steam-chest, is supported in a bearing formed on or secured to the main frame E.

A feed-water pump is mounted upon one of the runners, entirely disconnected from the 80 boiler. A steam-pump such as shown in Fig. 1 may be used, or a pump such as shown in Fig. 3, the plunger of which may be driven by a crank on the rock-shaft I through a suitable connecting-rod.

In case no feed-water heater is used, the steam-cylinder will be supported on a simple stand, which may extend across under the barrel of the boiler, and may be provided with a saddle for the support of such boiler, acting in 85 these respects just like the feed-water heater shown and described.

This portable engine, though it may be used anywhere, was especially designed for use in the forests, for operating portable saw-mills 90 and the like, where it has been found it is easier to transport an engine mounted on runners than one mounted on wheels. The diagonal arrangement of the steam-engine was adopted

in order that the steam-cylinder may be located as near the ground as possible, and the fly-wheel be made of comparatively large diameter and yet be high enough above the ground, so that the belt from it may clear all obstructions.

In the practical use of this portable steam-engine I have found that vibrations of the boiler due to the running of the engine are very much less than in any other portable steam-engine known to me; also, that the engine and boiler suffer less strain in transporting; also, that the engine will run with more steadiness, almost as steady as a true stationary engine seated on a fixed foundation.

Having thus described my invention, what I claim is—

1. The combination, substantially as before set forth, of the boiler, the runners, and the diagonally-arranged steam-engine, the cylinder end of which is supported on the runners and the main shaft across the top of the boiler.

2. The combination, substantially as before set forth, of the boiler, the runners, the diagonally-arranged steam-engine, and the transverse feed-water heater, which supports the barrel of the boiler as well as the cylinder end of the steam-engine.

In testimony whereof I affix my signature in presence of two witnesses.

JESSE WALRATH.
